Attorney

UNITED STATES PATENT OFFICE.

EVERT L. GENTRY, OF IDABEL, OKLAHOMA.

ARMOR FOR SHINGLES.

1,309,065.

Specification of Letters Patent. Patented July 8, 1919.

Application filed June 29, 1918, Serial No. 242,678. Renewed May 28, 1919. Serial No. 300,475.

To all whom it may concern:

Be it known that I, EVERET L. GENTRY, a citizen of the United States, residing at Idabel, in the county of McCurtain and 5 State of Oklahoma, have invented certain new and useful Improvements in Armors for Shingles, of which the following is a specification, reference being had to the accompanying drawings.

10 This invention relates to shingles, and particularly to armor therefor.

The general object of this invention is to provide metallic shingles or armor which may be placed over either clapboarding or 15 over wood shingles.

A further object is to so construct the metallic shingles that they will interlock either with the clapboarding or wooden shingle and also with each other.

20 A further object is to provide a metallic shingle or armor which will thoroughly protect the wooden shingle or clapboarding beneath and will rest firmly upon the structure beneath so as to prevent water percolating 25 in through the joints and rotting the wooden sub-structure.

Other objects will appear in the course of the following description.

My invention is illustrated in the accompanying drawings, wherein:—

Figure 1 is a side elevation of a portion of a roof having ordinary shingles thereon and covered with my improved armor;

Fig. 2 is a top plan view of my improved 35 armor;

Fig. 3 is a section on the line 3—3 of Fig. 2;

Fig. 4 is a section on the line 4—4 of Fig. 2; and

40 Fig. 5 is an enlarged fragmentary perspective view of the lower end of my improved armor.

Referring to these figures, it will be seen that my armor 10 is rectangular in form and 45 that at its lower edge it is formed with a relatively deep flange 11 the lower margin of which is inwardly turned as at 12, the ends of this inwardly turned margin 12 being cut away as at 13. The upper edge of 50 the armor is folded over upon itself as at 14, and this fold is pounded down until it fits tightly against the face of the armor.

The left hand edge of the shingle has an upwardly and inwardly extending marginal 55 bend 15 while the right hand edge of the armor has a downwardly and inwardly ex-

tending marginal bend 16. Where this armor is to be applied over old wooden shingles, the upper edge of the armor is inserted beneath one shingle, as for instance the armor 60 A and the middle shingle 10 is forced upward until the marginal flange 12 is forced beneath the butt or thickest portion at the lower edge of the shingle B in the manner illustrated in Fig. 1. Shingle nails 17 are 65 then driven through the metallic armor and through the wooden shingle and the shingle beneath and into the studding or sheathing C, this shingle nail however being disposed so as not to pass through the inwardly 70 turned flange 12. When the armor is applied to clapboards it is applied in the same manner as described for the application to ordinary wooden shingles.

It will be seen that this shingle is relatively small so that it may be readily handled and will not require long crates for shipping nor will it require any soldering. Furthermore, this armor may be applied to either old or new roofs, without the necessity of driving the nails to hold the shingler's stool. Furthermore, this armor may be used for the valley, hips and ridge of the roof thus permitting the job to be completed with one kind of shingle and eliminating the necessity of using "valley tin", ridge roll, flashing, etc. It will be seen that this armor fits closely down upon the wooden shingle so that no moisture can enter between the wooden shingle and the metal 90 shingle or armor.

The wooden shingles are practically enclosed within the metallic shingles or armor and thus are kept waterproof and dust-proof and as near air proof as is possible, 95 without the use of solder. This armor can be used for either what is known as "dimension" shingles or in "random" widths, thus giving the manufacturer a chance to work off scraps. Not only may this armor be 100 used for making valleys, hips and ridges, but it may be used for caps and all necessary flashing around flues, chimneys, bay windows, dormers and porches. The shoulder 14 formed by turning over the upper 105 edge of the armor prevents water from getting under the armor and the shingle does not require expert workmen to put it on.

I claim:—

1. As an article of manufacture, a metallic armor for wooden shingles comprising a rectangular sheet of metal having a down-

wardly extending flange at its lower end formed with an inturned margin, this flange having a depth equal to the thickness of the lower end of a shingle, the sides of the shingle armor having flanges adapted to interlock with the flanges on adjacent sheets.

2. The combination with a shingle of non-metallic material, of an armor therefor consisting of a rectangular sheet of metal superposed upon the shingle and formed at its lower end with a relatively deep flange having an inturned margin engaging beneath the shingle, one side edge of the sheet having an upwardly and inwardly turned flange

and the other side edge being provided with a downwardly and inwardly turned flange, whereby the side edge of one plate may be interlocked with the side edge of an adjacent plate, and fastening devices driven through said plate and through the shingle upon which the plate is applied.

In testimony whereof I hereunto affix my signature in the presence of two witnesses.

EVERT L. GENTRY.
